HIGH-FREQUENCY TRANSFORMER

Application filed May 31, 1929. Serial No. 367,530.

Our invention relates to inductances and high frequency current transformers. It relates more specifically to a type of inductance for use with a radio receiving system such as is described in our application Serial No. 331,210 filed January 9th, 1929, for the objects and purposes therein described.

One of the objects of our present invention is the construction of individual high frequency current transformers whose operation is perfectly efficient. A further object is the disposition of such transformers relative to one another in such a manner that their mutual inductance may be constant. Further objects include the coupling of such inductances in parallel and will appear more fully hereinafter.

While in the annexed drawings only one form of our invention is shown, corresponding parts and electrical equivalents are within the spirit of our invention including inferior structures and portions of such invention as shown.

In said annexed drawings:

25 Figure 1 is a front elevation of one of our improved transformer assemblies:

Figure 2 shows a vertical section on the line 2—2 of Figure 1, certain parts being shown in elevation;

30 Figure 3 is an enlarged axial section through one of the individual units of our transformer assembly;

Figure 4 is a horizontal section on the line 4—4 of Figure 1, showing the method of supporting the units;

35 Figure 5 shows a horizontal section on the line 5—5 of Figure 1, showing the method of completing the circular assembly;

Figure 6 is an enlarged view of a wedge 40 shown in Figure 5;

Figure 7 is a diagrammatic view of the wiring, each helix being indicated by a simple loop, and the number of transformer coils being less than the number shown in Figure

45 1 for the sake of clearness; and

Figure 8 is a side elevation of a smaller transformer built in accordance with this invention, having a section broken away to show a simpler form of transformer coil construction.

Referring to the same parts throughout the several views by the same reference characters we designate an antenna by the letter A in series with a variable condenser C¹, the ground side being joined to conductor 1 which is connected to one end of the circuit conductor 4 which is almost completely closed and is supported by the upper arm of the bracket 13 and the lower arm of bracket 12 in the manner shown in Figure 2, both brackets 55 being bolted to the base 11. The circular conductor 3 is the same size as conductor 4 and is supported by the upper arm of bracket 13 and the lower arm of bracket 12 on the opposite side of conductor 4. Conductor 2 is 60 connected to conductor 3 at the relatively opposite end from the junction of conductors 1 and 4. Conductor 2 is directly connected to the ground G.

Concentric with and inside of the conductors 3 and 4 are the conductors 5 and 6 supported by the lower arm of bracket 13 and the upper arm of bracket 12. The circular disc 9 is bolted vertically equidistant from conductors 3 and 5 and 4 and 6 to the bracket 12 70 as shown in Figure 4. The disc 9 is hollow in the center and has a V-shaped opening at the top in which the V-shaped piece 10 may be 75 slidably dovetailed when desired.

Single inductance units L consists of cylinders 14 having enlarged exterior peripheral abutments 15 at both ends so as to form a retaining guide for the layers of wire which consist of three single layers of insulated wire, each having the same number of turns. 80 The middle layer terminates preferably on the opposite side of the cylinder from the terminals of the inner and outer rows.

The ends 26 and 27 of the inner and outer helixes respectively passing through the 85 groove 21 of the peripheral abutment 15 and being connected to the external conductor 20. Similarly the opposite ends 24 and 25 of the inner and outer helixes pass through the groove 23 and are joined to the external conductor 19. The terminals of the single layer 90 pass through the grooves 16 and 22 and are soldered to the external conductors 17 and 18 respectively. The interior diameter of each single inductance unit L is preferably about 95 100

3½ inches so that its length will be relatively small in comparison with its cross section.

The width of the annular disc 9 measured in a radial direction is made the same as that of the inside diameter of the inductance units L so that it may snugly accommodate them when they are slid into position on the disc 9 through the V-shaped opening in the top. Inductance units L are slid to the lower or closed side of the annular disc 9 as close to one another as desired, care being taken that the electrically corresponding terminals of all coils are always on the same side, the terminals 19 and 20 connected with the inner and outer coils being shown on the inner sides. The last coil L is slipped over the V-shaped piece 10 which slides into the groove of the cylindrical section 9 and completes that circle. The connections 19 and 20 are bent laterally in opposite directions. Likewise, connections 17 and 18 are bent laterally in opposite directions, conductors 19 and 18 both bent rearwardly and conductors 20 and 17 being bent forwardly, being in the same direction. All of the conductors 19 are joined at substantially right angles with the circular conductor 5; conductors 20 with the conductor 6; conductors 18 with conductor 3 and conductors 17 with conductor 4. Conductors 7 and 8 are joined with the circular conductors 5 and 6 respectively at their relatively opposite ends preferably in the same manner as conductors 1 and 2 are connected to conductors 4 and 3. Thus the current path is equal in length and resistance for all inductance units and no variation in inductance from this cause is possible.

As depicted in Figure 8 each unit L consists of a primary helix P and a secondary helix S. The same relative ends of each primary helix are joined to conductors 3 and 4, and likewise, the same relative ends of the secondary helices are joined to conductors 5 and 6. Thereby the primary helices are connected in parallel as are the secondaries. In reading this figure attention is called to the fact that the terminals of the primary and secondary helices are on opposite sides of the unit L; that is, the primary terminals are shown in dotted lines.

By reason of the circular or annular disposition of the coils each inductance is similarly acted upon by all of the rest and no change in their individual inductances is possible from this cause. Such a disposition is necessary where a great number of coils are employed. Two such coils could be placed side by side without either diminishing the current or affecting the inductance of each.

The construction of each unit L permits of 100 per cent transfer of energy from primary to secondary. The inner and outer helices comprising the secondary absorb all

of the energy from the primary helix, being coupled as closely therewith as insulation and practical construction permits.

The value of this inductance is of special importance in combination with the circuit shown. Condenser C of Figure 7 is joined in parallel with the conductors 8 and 7 which form the output of the high frequency receiving system. The primary and secondary helices should preferably have the same number of turns so that there will be no transformation loss.

It is, of course, also apparent that each of the inductance units L, instead of being perfect transformers, could consist of primary and secondary coils loosely coupled together so that each inductance by reason of the transformation loss would in itself have characteristics tending to produce selectivity in a radio receiving system.

A satisfactory construction is shown clearly in Figure 8 in which individual primary and secondary inductances are shown preferably closely coupled together, although it is obvious that by changing the amount of flux interweaving each individual primary and secondary or by changing the amount of inductance in either they could be made so as to be loosely coupled.

Varying the angle formed by the axes of the primary and secondary coils, reducing the number of turns in either coil, thereby altering the inductances and spacing one coil from the other in order to reduce the intensity of the flux are common expedients for producing loosely coupled transformer coils.

Under all conditions, whether the coils be made as shown or loosely coupled, the individual inductance units L must be similar to each other, preferably identical, in self-inductance of both primary and secondary and mutual induction of primary and secondary, in order that there may be no loss when a great number of inductance units are employed to attain any desired degree of selectivity.

What we claim is:

1. A high frequency current transformer comprising a plurality of magnetically independent primary inductance elements joined in parallel and secondary inductance elements, each comprising two sections connected in parallel and severally coupled interiorly and exteriorly of each of said primary inductance elements, all of said secondaries being connected in parallel.

2. A high frequency current transformer comprising a plurality of independent equal primary inductance elements circularly disposed equidistant from each other on an annular disc; secondary inductance each comprising two sections connected in parallel and severally coupled interiorly and exteriorly of each of said primary inductance; and

- circular conductors disposed adjacent said annular disc to which the ends of both primary and secondary inductances are respectively joined.
- 5 3. A high frequency current transformer comprising a plurality of independent equal primary inductances circularly disposed equidistant from each other on an annular disc; two circular shaped conductors electrically disconnected at one point disposed adjacent both sides of said disc concentric with one another and one on either side being joined with said primary inductances; equal secondary inductances severally coupled in-
- 10 teriorly and exteriorly of each of said primary inductance, all being successively joined in parallel with the remaining circular shaped conductors; and output conductors for both primary and secondary circuits being joined at the relatively opposite ends of both primary and secondary circuits.
- 15 4. As an article of manufacture and sale a high frequency current transformer comprising a primary helix and secondary helices coupled interiorly and exteriorly thereof and joined in parallel.
- 20 5. As an article of manufacture and sale a high frequency current transformer comprising a plurality of independent equal primary inductances circularly disposed equidistant from each other on an annular disc; two circular shaped conductors electrically disconnected at one point disposed adjacent both sides of said disc concentric with one another and one on either side being joined with said primary inductances; equal secondary inductances severally coupled interiorly and exteriorly of each of said primary inductances all being successively joined in
- 25 parallel with the remaining circular shaped conductors; and output conductors for both primary and secondary circuits being joined at the relatively opposite ends of both primary and secondary circuits.
- 30 6. As an article of manufacture and sale a high frequency current transformer comprising a plurality of independent equal primary inductances circularly disposed equidistant from each other on an annular disc; two circular shaped conductors electrically disconnected at one point disposed adjacent both sides of said disc concentric with one another and one on either side being joined with said primary inductances and equal secondary inductances severally coupled with each of said primary inductances, all being successively joined in parallel with the remaining circular shaped conductors; and output conductors for both primary and secondary circuits being joined at the relatively opposite ends of both primary and secondary circuits.
- 35 7. A high frequency current transformer comprising a plurality of magnetically in-
- dependent equal primary inductance elements substantially disposed in a circle and equidistant from each other and equal secondary elements severally coupled with each of said primary inductance elements and joined in parallel.
- 40 8. A high frequency current transformer comprising a plurality of magnetically independent inductance elements joined in parallel and equal secondary elements each comprising two sections connected in parallel and severally coupled interiorly and exteriorly of each of said primary inductance, all of said secondaries being connected in parallel.
- 45 9. A high frequency current transformer comprising a plurality of magnetically independent equal inductance elements substantially circularly disposed radially equidistant from each other; equal secondary inductance elements severally coupled with each of said primary elements and severally intercepting the flux thereof and conductors disposed adjacent the ends of the inductance elements to which both primary and secondary elements are respectively joined.
- 50 10. As an article of manufacture and sale a high frequency current transformer comprising a plurality of magnetically independent equal primary inductances substantially circularly disposed equidistant from each other on an annular disc; two circular shaped conductors electrically disconnected at one point disposed adjacent both sides of said disc concentric with one another and one on either side being joined with the ends of said primary inductance; equal secondary inductances each comprising two sections connected in parallel and severally coupled interiorly and exteriorly of each of said primary inductance, all being successively joined in parallel with the remaining circular shaped conductors substantially as illustrated and described.
- 55 11. As an article of manufacture and sale a high frequency current transformer comprising a plurality of magnetically equal primary inductance elements disposed equidistant from each other on an annular disc; two circularly shaped conductors electrically disconnected at one point disposed adjacent both sides of said disc concentric with one another and one on either side being joined to the ends of said primary inductances; and equal secondary inductances severally coupled with each of said primary inductances, all being successively joined in parallel to the remaining circular shaped conductors severally coupled as illustrated and described.
- 60 12. A high frequency energy distributing device comprising a plurality of primary inductances of substantially equal inductance value and substantially electromagnetically independent but arranged to have their mutual stray fields equalized and said induc-

tances being electrically joined in parallel and secondary inductances severally coupled with each of said primary inductances and similarly disposed and joined in parallel.

5 13. A high frequency transformer comprising two primary helices of substantially equal inductance value and substantially electromagnetically independent but arranged to have their mutual stray fields equalized and 10 said inductances being electrically joined in parallel and secondary inductances of substantially equal inductance severally coupled with each of said primary inductances and joined in parallel.
